SYSTEM OF FIBER LIBERATION

Charles D. Altick, Lloyd D. Smiley, and Edward T. Turner, Dayton, Ohio, assignors to Pulp Process and Development, Inc., Dayton, Ohio, a corporation of Ohio

Application March 12, 1934, Serial No. 715,150

36 Claims. (Cl. 92—7)

The present invention relates to a system of preparation of pulp material for paper making and other purposes, and more particularly to a circulatory digester apparatus and method of fiber liberation by either sulphite, sulphate, or soda treatment. While, for illustrative purposes, the method and apparatus forming the subject matter hereof is herein described as pertaining to the treatment of wood chips for the preparation of cellulose, wood pulp, and the like, it is to be understood that the method and apparatus are not so limited, but are applicable also to the treatment of other fibrous, ligneous and cellulose materials.

Temperature, digester pressure, and concentration of acid in the cooking liquor, are three recognized controlling factors in digesting pulp material. It is equally important, however, that every portion of the mass shall be treated equally and subjected uniformly to the action of the cooking liquor.

In the usual methods of operation heretofore employed circulation and distribution of the cooking liquor throughout the mass is dependent upon convection currents and gas ebullition, and consequently some portions of the material lying inert within the tank may be under-cooked while other parts are over-cooked and, due to acid losses by evaporation, the cooking liquor varies in strength throughout the cooking operation.

In the present system the digester contents are maintained under a constant hydrostatic head or pressure whereby the liquor is caused to more thoroughly penetrate the material. The digester is filled full of material and the level of the cooking liquor is raised above that of the digester dome so that there is no space or low pressure area into which gases may rise within the digester. To insure intimate intermixture of the material and cooking liquor during the digesting process, material intermixed with liquor is positively circulated through the digester tank by being withdrawn at one end and reintroduced under pressure at the other end in a more or less continuous cycle of circulation. A portion of the cooking liquor is also circulated through the cooking mass under pressure additionally to such circulation of the intermixture of material and liquor by being withdrawn from the digester and reintroduced thereto under pressure and in a reheated condition either at the bottom or at any suitable elevation whereby the current of liquor and current of intermixture of material and liquor is withdrawn for circulation. The contrary currents meeting within the digester tank cause

such disturbance and agitation of the contents that every portion is brought into a zone of active treatment. After withdrawal from the tank the pressure upon the cooking liquor is temporarily reduced and the entrained gases are collected and condensed and the condensate is immediately returned to the liquor to maintain its required strength. Prior to introduction into the digester, the material is subjected to a pretreatment in a soak tank where it is saturated with cooking liquor. To insure uniform saturation of the material it is periodically circulated through the soak tank by being withdrawn from one end and reintroduced at the other in quite the same manner that it is later circulated through the digester tank.

The periods of circulation of the intermixture of material and liquor and that of the liquor alone are automatically controlled by suitable power switching means, either on a time basis or by volume control in which case a fluid meter is introduced into the circulatory cycle.

The object of the invention is to improve the apparatus as well as the means and mode of operation of digester cooking systems for pulp making operations whereby such apparatus will not only be cheapened in construction, but will be more efficient in use, uniform in action, economical in operation, automatic, and unlikely to get out of repair.

A further primary object of the invention is to enable the production of pulp of uniform character and quality.

A further and important object of the invention is the more rapid reduction of pulp at a lower cooking temperature and production of pulp of higher quality than now obtainable.

A further object of the invention is to reduce the time required for digestion of the material by providing better preparation of the material before its entry into the digester tank.

A further and important object of the invention is to effect thorough agitation of the material within the digester tank and to enable the cooking liquor to thoroughly and uniformly act upon every portion thereof.

A further object of the invention is to materially increase the yield of pulp for a given digester capacity by reducing the time requirement and by utilizing the entire digester space.

A further object of the invention is to provide an apparatus and method of treatment of fibrous material possessing the advantageous characteristics, features and steps as herein enumerated.

With the above primary and other incidental

objects in view, as will more fully appear in the specification, the invention consists of the features of construction, the parts and combinations thereof, and the mode of operation, or their equivalents, as hereinafter described and set forth in the claims.

In the accompanying drawings wherein is illustrated the preferred but obviously not necessarily the only form of embodiment of the invention, Fig. 1 is an elevation, somewhat diagrammatic, of an apparatus for carrying out the present process of treatment of pulp making material. Fig. 2 is a side elevation of a modification. Fig. 3 is a detail view of a variation of the automatic control means.

Like parts are indicated by similar characters of reference throughout the several views.

Although the present apparatus is primarily intended for the reduction of wood chips for production of paper pulp by the sulphite process, it is to be understood that it is not so limited, but may be employed for soda treatment or for sulphate treatment of not only wood chips but of fibrous material of other character in the preparation of pulp not only for paper making but for other purposes as the manufacture of nitrocellulose, cellulose acetate, pyroxylin, rayon, tannic extract, and other analogous materials. Therefore, the materials herein referred to are for illustrative purposes only and are not mentioned with intent to in any way limit the purpose, application, or result of the invention.

In the drawings, 1 indicates a storage or soak tank wherein wood chips or other fibrous material is initially stored until thoroughly saturated with water or other liquid. The preferable impregnant is the liquor in which the material is to be later cooked during the digesting process, which may be of either acid or alkaline character.

The storage or soak tank 1 comprises brick or other vitreous walls 2 enclosed in a thermally insulated jacket 3, and the contents of the tank are heated by heater coils 4 interiorly thereof or embedded within the vitreous walls 2 and controlled by a thermostatic valve 2a.

Surmounting the soak tank 1 is a condenser 5 by which vapors, arising from the tank 1, are condensed and the condensate returned to the tank. Leading from the bottom of the soak tank 1 is a conduit 6 communicating with a centrifugal pump 7, the discharge outlet of which is directed upwardly through the continuation 6a of the conduit 6, which is provided at its top with a lateral discharge outlet 8 communicating with the top of the soak tank 1 and having therein a cut-off valve 9. This forms a closed circuitous path, which includes the soak tank 1, through which the contents of the tank, consisting of pulp making material intermixed with impregnating liquid, is circulated by operation of the centrifugal pump 7. By operating the centrifugal pump from time to time to effect a circulatory motion of the intermixture of pulp making material and impregnating liquor during the process of preparation, the position of individual portions of the mass within the soak tank is changed and the contents agitated so that every portion of the material is subjected to uniform impregnating action of the liquor. This circulation of material in the preparatory stage not only insures more thorough and uniform saturation, but it also materially reduces the period of time necessary for proper preparation.

Leading from the top of the circulatory conduit 6a is a second outlet conduit 10, communi-

cating with the top of the digester tank 11 and having a cutoff valve 12. After the material has been retained in the soak tank 1 for sufficient period to become thoroughly saturated and impregnated with the liquor, which condition as before described is facilitated by the circulation of the intermixture of material and impregnating liquid, the valve 9 in the discharge outlet 8 back to the soak tank 1 is closed and the cutoff valve 12 in the discharge conduit 10 for prepared material is opened whereupon the material withdrawn from the bottom of the soak tank 1 is discharged through the conduit 6a and thence through the branch conduit 10 into the digester tank 11. The digester tank 11 may be of any convenient size and shape, that illustrated being a conventional form of digester having a domed top and conical bottom. At its bottom, the digester tank 11 is provided with the usual blow-off or discharge conduit 13, which in the present instance communicates with a centrifugal pump 14.

The centrifugal pump 14 discharges upwardly through the continuation 13a of the conduit 13 which, at its upper end, communicates with the supply conduit 10 discharging into the top of the digester tank 11. The circulatory conduit 13a is also provided with a branch 13b which discharges into the digester tank 11 at a point opposite the connection of the conduit 10. The conduit 10 is provided with a cutoff valve 15 intermediate the circulatory conduit 13a, and the branch conduit 13b is also provided with a cutoff valve 15a.

The digester tank 11, having been filled with prepared material, the valve 12 in the supply conduit 10 is closed and upon operation of the centrifugal pump 14, an intermixture of pulp making material and cooking liquor is withdrawn from the bottom of the digester tank 11 and discharged upwardly through the circulatory conduits 13a and 13b by which the intermixture of material and cooking liquor is returned to the top of the digester tank. These return conduits direct the intermixture in intersecting paths within the digester tank 11 thereby causing violent disturbance and agitation of the contents of the tank whereby every portion thereof will be uniformly subjected to the action of the heated cooking liquor. The conduits 13, 13a and 13b form, with the digester tank 11, a closed circulatory system of which the tank 11 is a part, through which the intermixture of material and cooking liquor may be circulated at will by operation of the pump 14. The digester tank 11 is provided at its top with a screen or baffle 16 for confining the pulp making material while allowing the cooking liquor to pass therebeyond. A cooking liquor conduit 17 leads, in elevated relation, from the top or dome of the digester 11, and is provided with an expansion valve or pressure regulator 18 by which the contents of the digester are maintained under predetermined hydrostatic pressure, which pressure falls somewhat in the conduit 17 beyond the valve or regulator 18.

The liquid level within the digester 11 is maintained well above the top of the tank so that there is no space within the digester into which gases and vapors may arise from the cooking liquor. Such vapors and gases, however, pass from the digester tank entrained with the liquor through the conduit 17 into a low pressure acid recovery compartment 19 into which the conduit 17 discharges. This recovery compartment 19 extends below the level of the top of the

digester and is so positioned as to contain a quantity of liquor, the fluid level of which is preferably above the outlet of the liquor conduit 17 which is submerged and fluid sealed thereby. The digester tank 11 being maintained entirely full of material and liquor and under pressure, there is little or no gas generation within the digester and consequent ebullition or bubbling, but as the liquor passes the pressure regulator 18 into a zone of lower pressure the hot volatile portions of the liquor expand into gas or vapors which are discharged below the liquid level of the recovery tank 19. This recovery tank 19 is provided with a baffle 20 to prevent violent agitation of the discharged liquor. The vapors and gases arising from the hot liquor at low pressure within the recovery compartment 19 arise into contact with the condenser coil 21 in the top thereof where they are condensed and the condensate returned to the body of liquor in the bottom of the recovery compartment. From the bottom of the compartment 19 there leads a suction or supply conduit 22 of a power pump 23 by which the liquor is returned to the digester under pressure through the conduit 24 communicating with the bottom of the digester tank 11.

Surrounding the conduit 24, there is preferably provided a heater unit 25 by which the returned cooking liquor is preheated before its entry into the digester tank. There is also provided in the return conduit 24 a check valve 26. There is thus established a circulatory system in which the digester tank is included and by which the cooking liquor is withdrawn from the top of the digester tank, the volatile gases condensed, and the liquor, restored to its original degree of concentration, is returned under pressure to the bottom of the digester tank in a reheated condition. The cooking liquor in this circulatory system moves in a direction contrary to the circulatory movement of the intermixture of material and cooking liquor through the tank and circulatory conduits 13, 13a and 13b. This contrary movement of the material and the liquor further insures thorough intermixture and uniform reducing action of the liquor upon every portion of the mass of pulp material.

In lieu of reheating the liquor by passing it through the heater unit 25, live steam may be introduced through the steam line 27, into the suction conduit 22, or into the return conduit 24, or, if desired, live steam may be introduced directly into the digester tank 11, which in either event intermixes with the liquor to raise its temperature.

As the spent liquor is discharged into the low pressure recovery compartment 19, the entrained gases arise, as before described, into contact with the condenser coils 21 in the upper portion and the condensed liquor and acid falls back into the lower part of the compartment to again enrich the cooking liquor and maintain its original concentration. However, any uncondensed vapors may escape from the recovery compartment 19 through the vent line 29, having therein a cutoff valve 30, through which they are conducted to a condenser or cooler 31 and returned thence to a liquor storage tank 32. The valve 30 of the vapor vent conduit 29 is to be opened and closed as the occasion may require. Within the storage tank 32 the cooking liquor may be preheated by suitable heating coils 33, and any vapors arising therefrom are condensed and re-

turned to the body of liquor by the condenser 34 in the top of the storage tank.

Leading from the bottom of the storage tank 32 is a supply conduit 35 communicating with a centrifugal pump 36, from the outlet of which extends two branch conduits 37 and 38. The conduit 37 is extended to the material storage or soak tank 1, with the top of which it communicates to supply impregnating liquor for saturation of the material preparatory to its treatment in the digester. In this supply conduit 37 to the soak tank is located a control valve 39 which, when closed, will divert the supply of liquor to the supply conduit 38 leading to the digester tank 11, to which cooking liquor may be supplied under pressure.

Communicating with the supply conduit 38 leading to the digester tank is an equalizer tank 40 wherein an excess of cooking liquor may be accumulated under pressure to maintain the supply to the digester tank 11 when the pump 36 is at rest or is being employed for supplying liquor to the soak tank. At such times the conduit 38 is closed by the valve 41. For illustrative purposes, the equalizer 40 is shown provided with a weighted piston 42 held in elevated position by the liquid pressure of the cooking liquor and which descends by gravity to force the liquor into the digester to maintain the predetermined hydrostatic pressure.

A blowoff conduit 43, having therein a valve 44, leads from the digester 11 back to the storage tank 32, through which the pressure within the digester tank 11 may be relieved and the surplus cooking liquor drained therefrom preparatory to discharging the completely digested material. Upon completion of the digesting operation, the valves 15 and 15a in the circulatory conduits are closed and an outlet valve 44' in the continuation 45 of the conduit 13a is opened, and by continued operation of the pump 14 the digested material is withdrawn from the bottom of the digester tank 11 and discharged thence through the outlet conduit 45 to suitable storage or washing tanks which, per se, form no part of the present invention and are not illustrated.

The circulatory systems pertaining to the storage or soak tank and to the digester tank although illustrated as interconnected component parts of a continuous unitary system, are shown in Fig. 1 as capable of simultaneous operation as separate units of such system. However, if the material in the preparatory process and that in process of digestion are to be circulated through successive periods and not simultaneously, the system may be much simplified and the necessity for one of the material pumps obviated by interconnecting the suction conduits from the bottoms of both the soak tank and the digester tank with a pump which will be common to both as is illustrated in Fig. 2. As is illustrated in Fig. 2, the centrifugal pump 1a is connected by the conduits 6 and 13 with both the soak tank and the digester tank and its discharge conduit 6a is connected as in Fig. 1 with both the top of the soak tank and the top of the digester so that by proper manipulation of valves, the partially processed material may be withdrawn from either of the tanks by the pump 1a and returned to the same tank in a continuous circulatory cycle, or at will the prepared material may be withdrawn from the bottom of the soak tank 1 and discharged into the top of the digester tank 11 for further processing. However, instead of being capable of simultaneous circulation, the material from the respective

tanks must be circulated successively but otherwise the operation and result is the same as before described.

The digester pressure and concentration of the cooking liquor and its temperature being uniformly maintained, the operation of this system becomes more or less routine and by periodic circulation of the material and the cooking liquor the batch time of preparation is materially reduced. When the time for preparation and proper digesting of a batch of particular material has once been determined, the periodic circulation may be made automatic by providing suitable control means for starting and stopping the driving motors of the respective pumps at predetermined time intervals. Such automatic control may be regulated either by a timing mechanism or by a meter introduced into one or another of the circulatory systems by which the fluid volume of the circulated liquor or material is measured and the period of circulation governed accordingly. Illustrative of such automatic control means, there is shown in Fig. 1 a clock work mechanism 46 including suitable speed reduction means by which there is driven a slowly rotating cam shaft 47 having thereon a series of adjustable cams 48 which, in the present instance, are arranged in pairs, the members of each pair being alternately engageable at predetermined time intervals with an alternating circuit make and break device controlling the electrical circuits to driving motors 51 for the several pumps. As illustrated in the drawings, there is provided a motor 51 for each of the pumps 7, 14 and 23, each having its independent energizing circuit 50, included in each of which is an oscillatory make and break switch 49. The contact cams 48 are adjustable to different radial positions about the slowly rotating control shaft 47 and may be adjusted thereon to operate the switches 49 in any predetermined sequence. As the shaft 47 rotates, one contact cam of each pair engages the movable switch member 49 to close the switch and energize the corresponding pump motor. After a predetermined period of operation determined by the relative radial positions of the cams 48 of the corresponding pair of such cam members, the other member of the pair will engage the switch member 49 to oscillate such member in reverse direction and open the circuit to stop the pump motor and so terminate the period of circulation of the stock or the liquor as the case may be.

In lieu of employing a clock work mechanism for rotating the cam shaft 49, a fluid meter 52 may be introduced into any one of the several circulation conduits and the slow motion cam shaft 49 may be operatively connected with such meter. In such case the switch operating cams 48 may be adjusted to open and close the respective switches in the motor circuit 50 when a certain quantity of material has been circulated. For example, the circulation of material may be continued until the entire contents of one or the other of the tanks have been passed through the meter one or more times, or until a certain proportion thereof has been withdrawn and returned to the tank to effect a corresponding displacement and intermixture of the contents within the tank.

In operation of the system, the storage or soak tank 1 is filled with chips or other fibrous material to be treated and an impregnating fluid, preferably the cooking liquor, is introduced into the tank 1 with the material and this intermixture is periodically circulated by operation of the centrifugal pump 7 until every portion of the mate-

rial is thoroughly saturated and in a partially softened condition. The valve 9 in the return connection 8 is then closed and the valve 12 in the discharge conduit 10 is opened, allowing the prepared material to be discharged directly into the digester tank 11. In this digester it is subjected as is usual to the reducing action of heat and cooking liquor. To facilitate the reduction and minimize the time required therefor, the material is periodically circulated by operation of the pump 14, causing the contents of the tank to be agitated and redistributed so that every portion thereof is uniformly subjected to the reducing action of the cooking liquor and the heat. As further facilitating this distribution of cooking liquor through the mass, the cooking liquor is drawn off from the digester tank 11 by being strained from the material at the top of the tank and the pressure thereon is temporarily relieved to permit volatilization of the gases which are immediately recondensed and returned to again enrich the liquor to its original degree of concentration, and such enriched liquor is returned in preheated condition to the digester.

During the period of digestion, the material within the tank 11 is maintained under hydrostatic pressure which insures the penetration of the cooking liquor into the pores of the fibrous material. When the treatment of the material is completed, the surplus cooking liquor is drained from the tank through the relief conduit 43 back to the storage tank 32 and the valves 15 and 15a being closed and the discharge valve 44 being open the continued operation of the pump 14 will discharge the finished products through the outlet conduit 45 to the washing tank or storage compartment. The circulation of the material and the liquor under pressure insures that every portion of the mass will be thoroughly permeated and uniform treatment will result. The temperature of the cooking batch is uniformly maintained by the frequent reheating of the liquor during its circulation which requires but slight rise in temperature and hence is quite economical. By utilizing the full capacity of the digester at each operation, the quantity of material treated is greatly increased and by circulation the period of treatment is materially decreased. The acid content of the liquor is maintained constant by preventing escape or release of gases and by recondensation and return of the acid vapors to the liquor as a part of the continuous cycle of operation. In this way the essential factors of heat, pressure, and acid concentration are uniformly maintained and in addition thereto thorough and uniform reduction action upon every part of the mass of material is insured, thereby resulting in a more rapid reduction of the material at a lower temperature and producing a much higher grade of pulp. The described method and apparatus effect material economy of operation and afford a better quality of products. Less steam than is ordinarily required is used for cooking and the temperature being maintained uniformly at the prescribed cooking temperature, there is less condensation within the digester, and the inflowing liquor being preheated and under pressure, objectionable water hammering is obviated. The maintenance of uniform temperature is conducive to longer usefulness and less deterioration of the digester and circulatory conduits which are highly susceptible to injury by rapid changes of temperature to which such apparatus has heretofore been subjected. The accurate and automatic control of the concentra-

tion and enrichment of the preheated liquor and the thorough agitation and intermixture of the liquor and material and periodic redistribution of the portions of the mass within the digester 5 tank incident to its circulation therethrough insures uniformity of successive cooks as well as uniformity of treatment of each particular batch operated upon and more complete digestion of material due to forced penetration of liquor and 10 equalized automatic control of successive batches.

The present system greatly facilitates the recovery of tannic acid from wood chips such as chestnut, oak, or the like, which may be introduced into the soak tank or storage tank 15 ! with an ample quantity of water and brought to a relatively high temperature by circulation of live steam through the coil 4. This, together with the agitation due to circulation of the material and impregnating liquid through the conduit 6 and 6a back to the tank through the discharge inlet 8, rapidly frees the tannic acid content of the material which may be drawn off from the tank ! in a relatively concentrated solution as 20 a valuable commercial by-product, leaving the pulp making material in a much improved condition. Thereafter cooking liquor may be intermixed with the material in the storage tank before introduction into the digester. For other 25 species of wood chips or other forms of pulp making material, cooking liquor may be introduced into the soak tank in lieu of water with the material supply, thereby insuring a thorough penetration of the cooking liquor into the pores of the chips.

30 When filling the digester tank 11 with the intermixture of pulp making material and cooking liquor, or other liquid as may be used, the intermixture will ordinarily be quite fluid and contain an excess of liquid. It is desirable to fill the 35 digester to the top with material. As the introduction of material continues, the excess liquid is displaced by pulp material and is conducted back to the storage or soak tank ! through the overflow pipe 16a. The screen 16 at the top of 40 the digester 11 strains out the returning liquid, 45 retaining the pulp material in the digester.

While in the drawings, for illustrative purposes the pumps 7 and 14 are shown arranged to withdraw material from the bottoms of the respective 50 tanks and return it to the tops thereof, and the pump 23 is arranged to return to the bottom of the digester, the liquor withdrawn from the top, it is to be understood that direction of operation 55 of the pumps may be reversed and the tanks maintained full, the intermixture of material and liquor may be withdrawn from the top of one or both tanks and returned to the bottoms thereof and that the direction of circulation of the cooking liquor independently of the material might 60 also be reversed. Such changes involving merely reversal of interconnections of the respective pumps without other material change of the apparatus or system are not illustrated.

65 The continued circulation of the partially digested material through the pump and the friction of the material within the circulatory conduit induces a disintegrating action or beating effect upon the material during the digesting 70 process, which not only hastens the digestion of the material but improves the quality and minimizes necessity for long subsequent beating or defibrating operations.

Not only is the digesting process improved and 75 shortened, but the entire process of pulp making

is materially cheapened and shortened and the quality of resulting product is materially raised.

From the above description it will be apparent that there is thus provided a device of the character described possessing the particular features 5 of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited 15 to the specific features shown, but that the means and construction herein disclosed comprise the preferred form of several modes of putting the invention into effect, and the invention is therefore claimed in any of its forms or modifications 20 within the legitimate and valid scope of the appended claims.

Having thus described our invention, we claim:

1. In an apparatus for treatment of pulp making material, a soak tank for preparation of material, a digester tank for the reduction of the prepared material, a circulatory conduit for an intermixture of material and liquid leading from one end of the soak tank and discharging into the opposite end thereof, a second discharge 30 connection from said circulatory conduit to the digester tank, a circulatory conduit for an intermixture of material and cooking liquor leading from one end of the digester tank and discharging into the opposite end thereof, and a circulatory 35 conduit for cooking liquor leading from one end of the digester tank and discharging into the opposite end thereof in reverse relation to the direction of circulation of the intermixture of material and liquor, and means for effecting circulation of material and liquor through the respective conduits.

2. In an apparatus for treatment of pulp making material, a digester tank, a conduit for an intermixture of material and cooking liquor leading 45 from one end of the digester tank and discharging into the opposite end thereof and forming a closed circulatory cycle including the digester through which material intermixed with cooking liquor is circulated, a separate conduit for cooking liquor 50 leading from one end of the digester tank and discharging into the opposite end thereof and forming a closed circulatory cycle including the digester through which cooking liquor is circulated apart from the material and means for inducing circulatory flow of material and liquor 55 in the respective conduits.

3. In an apparatus for treatment of pulp making material, a tank operative at substantially atmospheric pressure, a conduit for an intermixture of material and liquor leading from one end of the tank and discharging into the opposite end thereof and forming a closed circulatory cycle including the tank through which material intermixed with liquor is circulated, a heater 60 coil within the tank, a condenser for vapors arising from the tank connected therewith to return condensate to said tank, and means for inducing circulatory movement of the intermixture of material and liquor through the conduit and tank. 65

4. In an apparatus for treatment of pulp making material, a circuitous passage for an intermixture of material and cooking liquor and another circuitous passage for cooking liquor apart from the material, a portion of the circuitous 70 75

passages for material and for cooking liquor being in common wherein the cooking liquor is intermixed with the material, and means for inducing circulatory motion of the material and the 5 cooking liquor in the respective circuitous passages.

5. In an apparatus for treatment of pulp making material, a digester tank, a circulatory conduit for an intermixture of material and cooking 10 liquor leading therefrom and a multi-discharge connection of said conduit with the digester tank directing streams of material and liquor in intersecting paths within the digester tank to effect thorough agitation of the contents thereof, and 15 means for inducing a circulatory flow of material and liquor through the conduit from and thence back to the digester tank.

6. In an apparatus for treatment of pulp making material, a digester tank, a conduit for an 20 intermixture of material and cooking liquor leading therefrom, multi-discharge outlets from said conduit, one of which communicates with the digester tank for return thereto of unfinished product, and another of which leads away therefrom 25 for finished material, control means for directing the flow of material through the respective discharge outlets, and means for inducing flow of the intermixture of material and liquor through the conduit.

7. In an apparatus for treatment of pulp making material, a digester tank and a soak tank in 30 which material is prepared for admission to the digester tank, a conduit for pulp making material and a liquid in which the material is intermixed leading from the soak tank, multi-discharge outlets from said conduit, one of which communicates with the soak tank for the return thereto of incompletely prepared material and another of which communicates with the digester 35 tank for supplying thereto prepared material, control means for directing the flow of material through the respective discharge outlets and means for inducing a flow of the intermixture of material and soaking liquid through the conduit.

8. In an apparatus for treatment of pulp making material, a treatment tank to receive an 40 intermixture of material and treatment liquid, a circulatory conduit leading therefrom and returning thereto and forming therewith a closed 45 cycle circulatory system in which the tank is included through which the intermixture of material and liquid is circulated, means for inducing circulatory movement of the intermixture of material and liquid therethrough, and automatic control means for periodically initiating and arresting such circulatory motion.

9. In an apparatus for reduction of pulp making material, a tank, a normally open vent from the top of the tank to atmosphere, a conduit for 50 an intermixture of pulp making material and a liquid extending exteriorly of the tank from the bottom to the top thereof, and forming a closed cycle circulatory system including the tank through which the intermixture of pulp making 55 material and the liquid is circulated and a condenser associated with said normally open vent for condensation of vapors arising from the circulated material and from which the condensate is returned to the tank for maintenance of the 60 liquid content of the material substantially constant, and a pump for inducing a circulatory flow of such intermixture therethrough.

10. In an apparatus for preparation of pulp making material, a soak tank in which the material is saturated preparatory to digestion and

cooking operation, a conduit for an intermixture of pulp making material and soaking liquid extending exteriorly of the tank from the bottom and returning to the top of the soak tank and forming a closed cycle circulatory system in which the tank is included through which the intermixture of material and soaking liquid is circulated, means for maintaining the liquid contents of the material substantially constant by automatically returning thereto vaporized portions 10 arising therefrom and means for inducing a circulatory flow of the intermixture therethrough.

11. In an apparatus for the reduction of pulp making material, a digester tank, a circulatory conduit for an intermixture of pulp making material and cooking liquor leading therefrom and returning thereto and a circulatory conduit for cooking liquor apart from the pulp making material leading therefrom and returning thereto, the discharge outlets of the respective circulatory 20 conduits into the digester tank being arranged to direct streams of material and cooking liquor in intersecting paths within the tank to insure thorough intermixture thereof, and means for inducing circulatory motion of the material and 25 the cooking liquor through the respective conduits.

12. In an apparatus for treatment of pulp making material, a circulatory system for circulation of an intermixture of material in process 30 of preparation and soaking liquid, a circulatory system for an intermixture of material, in process of reduction, and cooking liquor, a circulatory system for cooking liquor apart from the material, means for inducing circulatory flow in 35 the respective systems, and automatic means for initiating and arresting the flow of material and liquids in the respective systems in predetermined sequence.

13. In an apparatus for treatment of pulp 40 making material, a circulatory system for circulation of an intermixture of material in process of preparation and a soaking liquid, means for inducing circulatory flow through such system, and automatic means for periodically initiating 45 and arresting the circulation through such system.

14. In a system of reduction of pulp making material, a tank to receive pulp making material intermixed with a liquid, a conduit leading from 50 the tank, alternative discharge branches of said conduit, one of which discharges back into the tank to afford a closed circulatory circuit for incompletely treated material and another of which branches affords a discharge outlet for completely 55 treated material, means for inducing the flow of material from the tank through said conduit and one of said branches, and selective means for said branches.

15. In an apparatus of the character described, 60 a soak tank for pulp making material, a thermal insulating jacket therefor, a supply conduit for impregnating liquid, and heater means for raising the temperature of the material and impregnating liquid during preparation of the material 65 for subsequent digesting operation.

16. In an apparatus of the character described, a digester tank, a conduit through which material is withdrawn from the digester tank, a plurality of discharge inlets through which material 70 may be simultaneously discharged into different portions of the digester tank and circulating means for returning to the digester tank through said plurality of inlets the material withdrawn from the tank through said withdrawal conduit 75

to thereby establish a circulation of material wherein the material will be agitated and mixed within the digester tank.

17. In an apparatus for treatment of pulp making material, a tank for receiving the material to be treated, a circulatory conduit for an intermixture of material and treatment liquid leading therefrom and returning thereto, means for inducing a circulatory motion of the intermixture of material and treatment liquid through the conduit and the tank, and means for automatically controlling the circulatory period.

18. In an apparatus for treatment of pulp making material, a tank for receiving the material to be treated, a circulatory conduit for an intermixture of material and treatment liquid leading therefrom and returning thereto, means for inducing a circulatory motion of the intermixture of material and treatment liquid through the conduit and the tank, including a motor driven pump and an electric motor therefor, an energizing electric circuit for the motor, a make and break switch therein, and means for automatically opening and closing such switch.

19. In an apparatus for treatment of pulp making material, a tank for receiving the material to be treated, a circulatory conduit for an intermixture of material and treatment liquid leading therefrom and returning thereto, means for inducing a circulatory motion of the intermixture of material and treatment liquid through the conduit and the tank, including a motor driven pump and an electric motor therefor, an energizing electrical circuit for the motor, a make and break switch in said circuit, a flow meter in said circulatory conduit, and switch operating means controlled thereby for automatically controlling the circulatory period.

20. In a system of the character described, a digester tank for pulp making material, a storage tank for a supply mixture of pulp making material and an impregnating liquid, a supply conduit leading from the storage tank to the digester tank for transferring the intermixture of material and impregnating liquid from such storage tank to the digester tank, and a return conduit from the digester tank to the storage tank for return of surplus liquid displaced from the digester tank by the introduction of additional material.

21. The herein described method of treatment of pulp making material including soaking the material in an impregnating liquid, heating the material and liquid independently of the circulation thereof, circulating an intermixture of the material and impregnating liquid during the soaking operation and then subjecting the soaked material to a subsequent digesting operation.

22. The herein described method of treatment of pulp making material including saturating the material with cooking liquor prior to a digesting operation, flowing an intermixture of material and cooking liquor through a circuitous path of travel during the saturation operation, maintaining the strength of the cook liquor substantially constant during circulation of the intermixture and then subjecting the saturated material to a digesting operation in the presence of heat and pressure.

23. The herein described method of treatment of pulp making material including subjecting the material to a digesting operation by cooking the material in a cooking liquor under hydrostatic pressure, withdrawing portions of the intermixture of material and cooking liquor from

the supply thereof and returning such withdrawn portions thereto through a circuitous path of travel under hydrostatic pressure during the digesting operation.

24. The herein described method of treatment of pulp making material including saturating the material in cooking liquor, circulating an intermixture of material and cooking liquor through a circuitous path of travel, by withdrawing successive portions thereof from the supply portion and progressively returning the withdrawn material thereto during the saturation period, maintaining the strength of the cooking liquor substantially constant during circulation, subjecting the saturated material to a digesting operation and continuing the circulation of the material and cooking liquor by withdrawing successive portions thereof from the supply portion and progressively returning the withdrawn portions thereto under hydrostatic pressure during the digesting period.

25. The herein described method of treating pulp making material including subjecting the material to a digesting operation under hydrostatic pressure, progressively withdrawing successive portions of material from the supply portion thereof being digested, subjecting the withdrawn portions to disintegrating action and progressively returning the partially disintegrated portions to the supply portion for further digestion while maintaining such material under hydrostatic pressure.

26. In an apparatus for treatment of pulp making material, a tank for containing pulp making material and an impregnating liquid, means for circulating an intermixture of the pulp making material and impregnating liquid, heater means for raising the temperature of the material and impregnating liquid during preparation of the material independently of the circulation thereof, and a condenser connected with the tank for returning thereto condensation of vapors arising from the impregnating liquid.

27. In an apparatus of the character described, a digester tank to contain an intermixture of material and treatment liquid, a circulatory conduit leading therefrom and returning thereto and forming therewith a closed cycle circulatory system in which the tank is included through which the intermixture of material and liquid may be circulated, means for inducing circulatory movement of the intermixture of material and liquid therethrough, and a second circulatory conduit leading therefrom and returning to the tank and forming a second closed cycle circulatory system in which the tank is included through which the treatment liquid may be circulated separately from the material, and means for inducing such independent liquid circulation.

28. In an apparatus for the treatment of pulp making material, a tank to contain an intermixture of pulp making material and treatment liquid, a circulatory system through which both pulp making material and treatment liquid may be progressively withdrawn from the tank and returned thereto, means for inducing circulation thereof, and means for heating the treatment liquid independently of the pulp making material.

29. In an apparatus for treatment of pulp making material, a tank to contain pulp making material and treatment liquid, a conduit leading from one end of the tank and discharging into the other end thereof for circulation of treatment liquid, a pressure operated valve restrain-

- ing the outflow of liquid from the tank and a pump for returning the withdrawn liquid thereto whereby the tank will be maintained completely filled with material and liquid under hydrostatic pressure.
30. In an apparatus for preparation of pulp material, a tank to contain an intermixture of pulp making material and treatment liquid, a storage reservoir for a supplemental supply of treatment liquid, a passage leading from the storage reservoir to the tank, a pump for supplying liquid from the reservoir to the tank through said passage, a return passage from the tank to the reservoir, and a condenser for vapors associated with said reservoir.
31. In an apparatus for preparation of pulp material, a tank to contain an intermixture of pulp making material and treatment liquid, a storage reservoir for a supplemental supply of treatment liquid, conduits connecting the supply reservoir and tank into a circuitous system, means for inducing a flow of liquid from the reservoir to the tank and thence back to the reservoir, and a bypass connection through which liquid discharged from the tank may be returned thereto without going to said supply reservoir.
32. In an apparatus for the treatment of pulp making material, a tank for containing pulp making material and an impregnating liquid heater means for raising the temperature of the material and impregnating liquid during preparation of the material, means for circulating the pulp making material and liquid independently of the operation of the heating means, and a condenser connected with the tank for returning thereto condensation of vapors arising therefrom.
33. The herein described method of treatment of pulp making material including subjecting the material to a digesting operation including cooking the material in a cooking liquor, withdrawing portions of the intermixture of the material and cooking liquor from the supply thereof, and returning such withdrawn portions thereto through a circuitous path of travel, and simultaneously withdrawing a portion of the cooking liquor independently of the material from the supply of intermixture of material and liquor and returning the withdrawn liquor thereto through a circuitous path in a direction opposite to the general direction of circulation of the withdrawn portion of the mixture of cooking liquor and material.
34. The herein described method of treatment of pulp making material including subjecting the material to a digesting operation including cooking the material in a cooking liquor, withdrawing portions of the intermixture of the material and cooking liquor from the supply thereof and returning such withdrawn portions thereto through a circuitous path of travel, and simultaneously withdrawing a portion of the cooking liquor independently of the material from the supply of intermixture of material and liquor and returning the withdrawn liquor thereto through a circuitous path in a direction opposite to the general direction of circulation of the withdrawn portion of the mixture of cooking liquor and material.
35. The herein described method of treatment of pulp making material including subjecting the material to a digesting operation by cooking the material in a cooking liquor, withdrawing a portion of the intermixture of material and cooking liquor from the bottom of a digester and returning it to the top thereof and simultaneously withdrawing a portion of the cooking liquor independently of the material from the top of the digester and returning it to the bottom thereof during the digesting operation.
36. The herein described method of treatment of pulp making material including subjecting the material to a digesting operation including cooking the material in a cooking liquor, withdrawing portions of the intermixture of the material and cooking liquor from the supply thereof and returning such withdrawn portions thereto through a circuitous path of travel, and simultaneously maintaining the intermixture of cooking liquor and material under hydrostatic pressure during circulation.
